FIG. 2

FIG. 1

FIG. 3

To all whom it may concern:

Be it known that I, Carl W. Sundberg, a citizen of the United States and a resident of the city of Birmingham, in the county of Oakland and State of Michigan, have invented a new, original, and ornamental Design for a Combined Washing Machine and Wringer, of which the following is a specification, reference being had to the accompanying drawing, forming a part thereof.

On the drawing:

Figure 1 is a front perspective view of the combined washing machine and wringer showing my new design;

Figure 2 is a rear perspective view thereof; and Figure 3 is a view of one end of the wringer member shown in Figures 1 and 2. The other end is the same but without the control member.

I claim:

The ornamental design for a combined washing machine and wringer, as shown and described.
